UNITED STATES PATENT OFFICE.

JOSEPH F. DWYER, OF SEATTLE, WASHINGTON.

TICKET-DISPENSING MACHINE.

1,334,653.

Specification of Letters Patent. Patented Mar. 23, 1920.

Application filed April 24, 1919. Serial No. 292,501.

To all whom it may concern:

Be it known that I, JOSEPH F. DWYER, a citizen of the United States, residing at Seattle, in the county of King and State of Washington, have invented a certain new and useful Improvement in Ticket-Dispensing Machines, of which the following is a specification.

My invention relates to improvements in ticket dispensing machines which shall be adapted to contain and dispense tickets, postage stamps, labels and the like and the object of my invention is to provide a ticket dispensing machine that is simple in its plan of construction efficient in its operation and inexpensive to manufacture. A further object is to provide a simple and efficient ticket dispensing machine which shall be adapted to dispose the end of a ticket, postage stamp, label or the like in a protected exposed position whereby it may readily be withdrawn therefrom. A still further object is to provide a device wherein the ticket, postage stamp, label or the like may be disposed therein or withdrawn therefrom without disassembling said device, and consists in the novel construction, adaptation and arrangement of parts as will be more clearly hereinafter described and claimed.

30 I accomplish these objects by devices illustrated in the accompanying drawings, wherein—

Figure 1 is a view in perspective of a ticket dispensing machine embodying my invention;

Fig. 2 is a view in cross-section substantially on broken line 2, 2 of Fig. 1; and

Fig. 3 is a fragmentary view in perspective illustrating a detail of my invention.

40 Referring to the drawings, throughout which like reference numerals indicate like parts, 6 designates the bottom wall of a receptacle that is provided with two end walls 7 and 8, a front wall 9 and a top and back wall 10 said top and back wall 10 being rigidly secured together and being hingedly secured to the bottom wall 6 as indicated at 11 whereby entrance to the interior of said receptacle may be gained by swinging said 50 top and back wall 10 rearwardly into a position shown by dotted lines in Fig. 2.

The front wall 9 is provided, a short distance from the top thereof, with an inclined shelf that is formed with a plurality of grooves 12 that are spaced apart by ribs 13 which grooves 12 communicate at their up-

per ends with the interior of the receptacle by slots 14.

The grooves 12 are of suitable width to receive tickets that are in the well known 60 form of a strip or ribbon 15 of paper or cardboard, that may be rolled and placed upon a shaft 16 which is disposed within and is supported by slots 17 that are formed in partitions 18, which slots 17 extend forwardly to the central portion of said partitions 18 whereby they may be turned downwardly as at 19 if desired to provide a better bearing for the shaft 16. The partitions 18 are secured rigidly and permanently to the 70 bottom wall 6 and front wall 9 of the receptacle.

Disposed above the partition walls 18 and adjacent the slots 14 is a guide member 20 which may be either a rotatably mounted or 75 a fixedly mounted roller and over which the ticket ribbons are caused to pass as they are drawn from the machine.

Secured to the top member 10 are a plurality of tension springs 21, one above each 80 roll of tickets, that are arranged to engage the top of the ticket ribbons 15 as they pass over the guide 20 and that exert sufficient pressure on such ticket ribbons to prevent them from pulling outwardly easily or from 85 being pushed backwardly into the receptacle.

The slots 12 are preferably covered by a transparent plate 22 that rests upon the ribs 13 and is held in position by cleats 23, the 90 transparent plate permitting the ticket ribbons to be seen before they are withdrawn and the forward edge of such plate facilitating the tearing off of the ticket ribbon.

In filling the machine the top and back 95 member 10 may be moved downwardly, the ticket rolls placed on the shaft 16, the shaft inserted into the slots 17, the ends of the ticket ribbons passed over the guide 20 and outwardly through the slots 14 and the top 100 and back member 10 swung upwardly into place.

In removing tickets the finger may be inserted under the edge of plate 22, the ticket ribbon grasped and any desired length of 105 such ticket ribbon removed and torn off by drawing it upwardly against the edge of the plate 22.

Obviously changes may be made in the precise form of construction and arrangement of parts of my invention without departing from the spirit thereof.

What I claim is:

A ticket dispensing machine comprising a box like receptacle provided with slots through which ticket ribbon may be extracted and having a top wall and rear wall that are rigidly secured to each other and are hinged to the lowermost rear edge of said receptacle; spaced apart vertical partitions secured to the bottom and front walls 10 of said receptacle, said partitions having

horizontal slots that extend forwardly from the rear edge thereof and offset recesses at the forward end of said slots; and a shaft arranged to have rolls of ticket ribbon placed thereon and to be inserted within 15 the offsets of said slots, said offsets forming bearings for said shaft.

In witness whereof I hereunto subscribe my name this 19th day of April, A. D. 1919.

JOSEPH F. DWYER.
